RITCHIE S. GALLOP, OF VICTORIA, BRITISH COLUMBIA, CANADA.

SPARKING DEVICE FOR INTERNAL-COMBUSTION ENGINES.

1,322,687.

Specification of Letters Patent.

Patented Nov. 25, 1919.

Application filed February 12, 1917. Serial No. 148,208.

To all whom it may concern:

Be it known that I, RITCHIE S. GALLOP, a subject of the King of Great Britain, residing at Victoria, in the Province of British Columbia and Dominion of Canada, have invented certain new and useful Improvements in Sparking Devices for Internal-Combustion Engines, of which the following is a specification.

10 This invention relates to internal combustion engines, and particularly to the ignition systems therefor.

The primary object of the invention is to provide an improved spark plug for use 15 in connection with the explosive cylinder of an internal combustion engine, and which is capable of being examined, cleaned, or repaired without removing the plug from the cylinder. A further object of the invention is to provide a plug of this character which includes a plurality of separate and distinct spark points, and which is capable of being readily actuated so as to dispose any of the sparking gaps in communication with the explosive cylinder. A still further object of the invention is to provide in a spark plug of this character, improved means for establishing an electrical connection between the source of energy and that pair of points only which is in communication with the explosive cylinder.

Still further objects reside in providing a mechanism of this character which is capable of being constructed so as to be applicable to cylinders of engines now in use; which requires no change in the wiring of the ignition system, which is capable of being manufactured at comparatively low cost; which may be quickly and easily attached to or detached from the engine cylinder when required; which is simple of construction and operation; and which will prove thoroughly efficient in the attainment 45 of the ends for which it is designed.

In the drawings:—

Figure 1 is a top plan view of a portion of an internal combustion engine, and illustrating the application of a sparking mechanism constructed in accordance with the invention;

Fig. 2 is a sectional view taken substantially on the line 2—2 of Fig. 1;

Fig. 3 is a view of one end of the spark-55 ing device; and

Fig. 4 is a similar view of the opposite

end of the sparking device with the retaining cap removed.

The invention in its preferred embodiment includes a barrel, body portion or 60 casing indicated at 5, and which is provided with a laterally projecting tubular or stem portion 6. The tubular portion is threaded upon its exterior surface so as to be capable of being screwed within the 65 spark plug opening of the combustion engine cylinder. The casing 5 is provided at a point preferably diametrically opposite to the point of communication of the stem 6 therewith with an upwardly disposed flange 7, and a lid 8 is hinged to the flange and is capable of closing the opening defined thereby.

This casing is constructed preferably of metal, but it is obvious that other materials 75 may be used if desired.

Rotatably mounted within the barrel or casing 5 is a spark plug, in the form of a core 9. This core is constructed of suitable non-conducting material, and is of a size 80 to fit snugly within the barrel. This core is provided with notched or cut away portions 10, the said portions being so located upon the core as to be capable of opening into the hollow stem portion 6 and the opening defined by the flange 7, and within each of the notched portions is located a pair of sparking points 11. The sparking points in the present instance are formed by extending conductors 12 longitudinally of the 90 core and spaced inwardly from the outer surface of the latter. One end of each of the conductors extends outwardly as at 13, and engages with the inner wall of the metallic casing 5. The opposite ends of the 95 conductors project beyond the extremity of the core and provide contact points 14.

The end of the core opposite to that at which the contacts 14 are located is provided with a turn key 15, by means of which 100 the plug may be readily rotated. Adjacent the last named end of the core and projecting from one side thereof is a pin or projection 16, which is adapted to engage stops 17 formed on the end of the casing or barrel 105 5. The projection and stops 16—17 are so arranged that when engaged, one of the notched portions 10 of the core will be in communication with the hollow stem 6, while the other notched portion will be disposed directly beneath the lid or cover 8 of the casing. When the plug is rotated so

that the projection 16 is engaged with the oppositely arranged stop, the notched portions 10 will be in reverse position.

The means by which the conductors 12 are operatively connected with the ignition system includes a standard 18 secured to and insulated from the cylinder of the engine adjacent the contacts 14 of the rotatable plug. This standard is yoked at its upper portion so as to provide a pair of spaced arms, within which the protruding contacts 14 upon the core are confined. These contacts however can only engage the standard 18 one at a time, and the arrangement is such that one or the other of the contacts is engaged only when the plug has been rotated to its extreme limit in one direction or the other. The standard 18 constitutes a terminal of the ignition circuit, and it is apparent from the foregoing that only those sparking points which are in communication with the hollow stem 6 are energized.

Any approved means can be employed for maintaining the core in proper position within the casing 5, but in the present instance, a detachable ferrule 20 is threaded upon one end of the barrel and encloses the adjacent end of the core, while a nut 21 is threadedly engaged with a reduced portion at the opposite end of the core. The ferrule and nut prevent movement of the core longitudinally of the casing, but permit of the core being freely rotated.

When the standard 18 is properly connected with a source of energy and the core 9 has been rotated to its limit in one direction, it is apparent that one of the contacts 17 will be engaged with the terminal 18 so that the electrical circuit is completed; it being understood of course, that the circuit will be grounded through the engine cylinder by reason of the constant engagement of the end 13 of the conductor with the casing or barrel 5. When in the position indicated in Fig. 2, the spark gap at the lower side of the core will be in direct communication with the interior of the cylinder, while the gap at the upper part of the core will be disposed beneath the lid or cover 8. Should it be desired to clean or repair the spark points 11, the lid may be raised, whereby access may be readily had to the said point.

From the foregoing it is apparent that I have provided an extremely simple and yet thoroughly efficient means for the attainment of the ends set forth. The plug may be readily turned when it is found that the sparking points at one side thereof are inoperative. The plugs may be readily detached from the casing when desired, so as to be supplemented by new plugs. I have described the plug or core in the present instance as being provided with a pair of conductors 12, but it will be understood that any desired number of such conductors may

be provided upon the core if found expedient.

While the present disclosure is that of what I believe to be the preferred embodiment of the invention, it is to be understood that the invention is not limited thereto, but that various changes may be made in the construction, arrangement, and proportion of parts, without departing from the spirit of the invention, as defined in the appended claims.

It will be seen that the device is especially adapted for use with motors of aeroplanes, as the plug may be turned in flight should engine trouble or fouling occur, and this will obviate the necessity of descending and alighting to make repairs, as by changing the ordinary type of plugs. The notches or cut away portions 10 also produce cups permitting the electrodes to be primed by opening the cover or lid 8, so that when the plug is turned a half revolution the sparking system will be operative and operation of the motor may be continued. The uppermost electrodes may also be conveniently cleaned of carbon deposit, corrosion or other foreign matter, by opening the cap 8, so that it will always be ready for use, inasmuch as any or all of the plugs may be changed to bring into operative position a clean set of electrodes, without the necessity of stopping the engine.

What is claimed is:—

1. The combination with a combustion engine cylinder; of a core rotatably mounted on said cylinder transversely of the axis thereof, sparking points arranged in pairs upon said core and being adapted one pair at a time to be placed in communication with the interior of said cylinder without removing the same, and means for closing an electric circuit through each pair of points when one of such pairs are in communication with the interior of said cylinder.

2. The combination with a combustion engine cylinder; of a core rotatably mounted on said cylinder transversely of the head thereof, sparking points arranged in pairs axially upon said core and being adapted one pair at a time to be placed in communication with the interior of said cylinder, a terminal, and the points of each pair being connected with said terminal when in communication with the cylinder.

3. The combination with a combustion engine cylinder; of a core rotatably mounted diametrically for rotation at right angles to the circle thereof on said cylinder, a plurality of conductors longitudinally on said core, each conductor having a spark gap adapted to be placed in communication with the interior of said cylinder upon rotation of said core, a terminal, and the said conductors being engaged with said terminal when

the spark gaps therein are in communication with the interior of the cylinder.

4. The combination with a combustion engine cylinder; of a spark plug rotatably mounted on said cylinder substantially tangentially to the head thereof and being in communication with the interior thereof, sparking points arranged in pairs on said plug transversely to the axis of the cylinder and being adapted upon movement of the latter to be placed selectively in communication with the interior of said cylinder, and means for closing a circuit through said points when the latter are in communication with the cylinder.

5. The combination with a combustion engine cylinder; of a spark plug rotatably mounted upon said cylinder across the axis thereof, sparking points arranged in spaced relation upon said plug and adapted upon movement of the latter to be placed one pair at a time in communication with the interior of the cylinder at the head thereof, means for limiting the movement of said plug, and the said points being in communication with a source of electrical energy only when in communication with said cylinder.

6. In a device of the class described, a casing, a stem projecting laterally from the casing, a core rotatably mounted in said casing at right angles to the stem, a pair of spark points carried by said core and being adapted upon rotation of the latter to be moved into and out of communication with said stem.

7. In a device of the class described, a casing, a hollow stem projecting laterally from said casing, a core of insulating material rotatably mounted in said casing and intercepting the stem, the said core being provided with spaced recesses, spark points in said recesses, the said recesses being adapted upon rotation of said core to move into or out of communication with said stem,

and means for limiting the movement of rotation of said core in either direction.

8. In a device of the class described, a casing, a hollow stem projecting from said casing, a core rotatably mounted in said casing, spark points carried by said core and being adapted selectively to be brought into communication with said stem, and a ferrule for holding said core against longitudinal movement within said casing.

9. In a device of the class described, a hollow casing, a hollow stem communicating with said casing at one side thereof and intermediately its ends, a core rotatably mounted in said casing at right angles to the axis thereof, conductors in said core, the said conductors being provided with spark gaps adapted upon rotation of the core to be moved selectively into communication with said hollow stem, and the ends of said conductors projecting from said core for co-operation with a circuit closer.

10. In a device of the class described, a hollow casing, a hollow stem communicating with one side of said casing, the said casing being provided with an opening, a core rotatably mounted in said casing, pairs of spark points carried by said core and being adapted upon rotation of said core to move into communication with said stem, a nut threaded on one end of said core for holding the latter against movement longitudinally of the casing, means for holding said core against longitudinal movement, one of each of said pairs of spark points engaging the casing and a contact member for engagement by the other spark points independently.

In testimony whereof I affix my signature in presence of two witnesses.
